UNITED STATES PATENT OFFICE.

ANDREW SHEARER, OF FRANKFORT, KANSAS.

LISTER-PLOW.

1,258,951.

Specification of Letters Patent. Patented Mar. 12, 1918.

Application filed January 2, 1917. Serial No. 140,131.

To all whom it may concern:

Be it known that I, ANDREW SHEARER, a citizen of the United States, and a resident of Frankfort, in the county of Marshall and 5 State of Kansas, have invented certain new and useful Improvements in Lister-Plows, of which the following is a specification, reference being had to the accompanying drawings.

10 My invention relates to lister plows of the general type shown in patent to me No. 894,802, granted July 28, 1908, and it has for one of its objects the provision of a new and improved form and arrangement of 15 parts for connecting the beam of the plow to the framework and for connecting the draft means to said parts, whereby in operation the plow-body will assume and maintain as nearly as possible the same angular 20 position relative to the frame whether plowing deep or shallow. It is another object of my invention to provide a construction in which the plow may be handled more readily by the operator, this result being attained 25 in the construction employed by me by reason of the draft being applied both to the frame and to the plow-beam, permitting the more ready control of the plow-body relative to the frame. It is another object 30 of my invention to provide a construction by reason of which the forward one of the beam-supporting members becomes an evener and suction device combined in one, preventing longitudinal rocking of the beam, insuring correct suction of the plow-body and 35 ease of entering the ground, and relieving the lifting lever of the strain of pulling the frame through the medium of the bail. It is another object of my invention to improve 40 devices of this type in sundry details hereinafter pointed out. The preferred means by which I have accomplished my several objects are illustrated in the drawings and are hereinafter specifically described. That 45 which I believe to be new and desire to cover by this application is set forth in the claims.

In the drawings:—

Figure 1 is a top or plan view of a lister plow embodying my improved construction; 50 and

Fig. 2 is a side view of the plow shown in Fig. 1, with one of the supporting wheels removed therefrom for the sake of clearness of illustration.

55 In the drawings,—10 indicates a frame member comprising side bars converging

toward their rear ends which are joined together on opposite sides of a bracket 11. A cross-bar 12, preferably in the form of an arch, has its end portions connected to the 60 side bars of the frame 10 by means of brackets 13—14. A second cross-bar 15, also preferably in the form of an arch, is secured in position upon the cross-bar 12, the outer ends of the cross-bar 15 being connected by 65 means of diagonally-disposed brace-bars 16—17 with the adjacent portions of the frame member 10. Axle members 18—19 are revolvably mounted at opposite sides of the machine, each of such axle members being 70 journaled in a suitable bracket 20 secured between the outer ends of the diagonally-extending brace-bars 16—17 and in the adjacent one of the brackets 13—14. The axle members 18—19 are provided with 75 carrying wheels 21—22 upon offset portions of such axle members.

The position of the carrying wheels 21—22 is controlled by means comprising a lever 23 fixedly mounted upon a rock-shaft 24 80 which is journaled upon the cross-bars 12 and 15. The lower end of the lever 23 is connected by means of a link 25 with the end of an arm 26 formed with or otherwise fixedly connected to the axle member 19. 85 The rock-shaft 24 is connected with the axle member 18 by means of a link 27 pivotally connected to arms 28—29 formed with or otherwise fixedly connected to the rock-shaft 24 and the axle member 18 respectively. The 90 construction and arrangement are such that when the lever 23 is given a stroke relative to the framework, one of the wheels 21—22 is moved upward relative to the frame while the other is moved downward. The lever 95 23 is adapted to be held in adjusted position by a suitable engagement with a segmental rack 30 carried by the framework.

The bracket 11 at the rear end of the frame has pivotally mounted in it a suitable 100 axle member 31, upon the lower end of which caster wheels 32 of any suitable type are journaled. The bracket 11 also serves to support a seat 33 for an operator within suitable reach of the lever 23, stirrups 34 105 being provided upon the frame for the feet of the operator.

The construction and arrangement of the parts so far described are substantially the same as that shown and described in an application by William S. Graham, for patent 110 upon lister plows, Serial No. 31,156, and

such subject-matter forms no part of my invention.

A double mold-board lister plow-body 35 is suitably secured upon the rear end of a plow-beam 36. The beam 36 is journaled by means of suitable brackets 37 upon an offset portion of a bail 38 which is journaled between the side bars of the frame member 10. The bail 38 is adapted to be turned for moving the plow-body 35 up and down relative to the frame 10 by means of a lever 39 fixed upon one end of said bail, said lever being adjustable along a segmental rack 40 carried by the framework. A coiled spring 41 is connected at its rear end to an arm 42 secured upon one end of the bail 38, said spring being secured at its forward end to a bracket 43 mounted upon the framework. This spring serves to assist in lifting the beam 36 and the plow-body 35 relative to the framework.

The forward end of the plow-beam 36 is held in position relative to the forward end of the frame member 10 by means of a link 44 the forward end of which is pivotally connected to the beam by means of a pin 45 and the rear end of which is pivoted by means of a pin or bolt 46 passing through a bracket 47. The link 44 has pivotally connected to it at a point intermediate of its ends a draft device 48 which in turn is adapted to be connected with any suitable source of power.

By the provision of the form and arrangement of parts disclosed in the drawings, in which the normal line of the link 44 between the pivot pins 45 and 46 extends substantially parallel with the crank portion of the bail 38, the angular position of the plow beam and the plow carried thereby remains approximately constant as the plow-body is raised and lowered relative to the frame from the position shown in Fig. 2 for varying the depth of plowing. When, however, the lever 39 is swung in clockwise direction, in Fig. 2, for raising the plow body out of operative engagement with the ground, the link 44 and bail 38 coöperate in such a manner as to hold the forward end of the beam 36 substantially in fixed position while the beam as a whole practically pivots about the pin 45, this result being attained by reason of the link 44 being of greater length than the crank arm of the bail. It will also be noticed that when the plow is lifted from engagement with the ground, so as to pivot about the pin 45, as just stated, the point of the plow will be directed downwardly so as to facilitate its entrance into the surface of the ground when the plow is again lowered by a movement of the lever 39 in a counter-clockwise direction; although it is to be understood that as soon as the plow enters the ground, it assumes its normal plowing position and that by virtue of the position of the link 44 with relation to the crank of the

bail 38, as above explained, the plow will be maintained in its normal angular position relative to the frame regardless of any adjustment of the plow to effect deep or shallow plowing. By reason of the connection of the draft device with the link between the frame 10 and the beam 36 rather than with either of said parts to the exclusion of the other, the plow is more readily moved relative to the frame than would be the case if the entire machine were drawn from the beam.

What I claim as my invention and desire to secure by Letters Patent, is—

1. In a lister plow, the combination of a frame, a crank bail on the frame normally extending at an angle to the vertical when the plow is in its normal plowing position, a plow-beam secured to the crank of the bail and movable therewith up and down relative to said frame, a plow body carried by said plow-beam, a link normally extending in a line parallel with the crank of said bail, said link being pivotally connected to said plow-beam and pivotally connected to said frame at a point above and to the rear of the point at which it is connected to said plow-beam, and a draft appliance connected to said link at an intermediate point therealong. 95

2. In a lister plow, the combination of a frame, a plow-beam, a plow body carried by said beam, a crank bail pivotally connecting an intermediate portion of said plow-beam with said frame, a link in the front of said bail pivotally connecting said plow-beam with said frame and normally extending in a line parallel with the bail when the plow is in normal plowing position, said link being substantially twice as long as the crank of said bail whereby the plow-beam pivots about its pivot with the link to permit the plow to be raised to the proper height above the ground and whereby the plow, when so raised, has its point extending downwardly 105 to enter the ground, and a draft appliance connected to said link between its pivotal connection to said frame and said plow-beam for applying power to both. 110

3. In a lister plow, the combination of a frame, a plow-beam, a plow-body carried by said plow-beam, a crank bail pivotally connecting an intermediate portion of said plow-beam with said frame, and a link pivotally connecting the forward end of said 115 plow-beam with said frame and extending substantially parallel with the crank bail, said link being of greater length than the crank arm of said bail, and serving as an evener between the beam and the frame and as a means in connection with the bail for controlling the suction of the plow-body and for insuring the plow-body being lifted to the proper height for the turning of the machine. 120 125 130

4. In a lister plow, the combination of a frame, a crank bail on the frame and normally extending forwardly with a downward slant when the plow is in normal plowing position, a plow-beam secured to the crank of the bail and movable therewith up and down relative to the frame, the forward end of the plow-beam being arranged to lie below the frame, a plow body carried by the plow-beam, a link normally extending parallel with the crank of said bail and of greater length than said crank, said link being pivotally connected at its forward end to said beam and having its rear end portion pivotally connected to said frame at a point above and to the rear of its connections with said plow-beam, and means for rotating the crank bail. 10
